UNITED STATES PATENT OFFICE.

LESLIE A. RAWSON, OF VENICE, CALIFORNIA. ASSIGNOR TO EMSCO DERRICK & EQUIPMENT COMPANY, OF LOS ANGELES, CALIFORNIA, A CORPORATION OF CALIFORNIA.

STEEL DERRICK CONSTRUCTION.

Application filed June 13, 1925. Serial No. 36,901.

My invention relates particularly to steel derricks such as those employed in the well drilling industry. An example of the use of a steel derrick to which my invention applies is in the oil well industry. A derrick is installed previous to the drilling of the well for the purpose of handling the various casings and equipment employed during the drilling, and also during the pumping of the well. During the drilling of the well, the derrick is called upon to handle enormous loads and is subjected to great strains. For example, it is sometimes necessary to pull a casing which has been "frozen." After the well is drilled and the casing is set in place, the derrick is not called upon to handle extremely heavy objects. During the pumping of the well, it is only necessary to handle the pump tubing and rods which are comparatively light as compared with the drill pipe and other drilling equipment. If the derricks are made sufficiently heavy to withstand the great strains to which they are subjected during the drilling of a well, they are much heavier than is necessary during the pumping period of the well. As a matter of economy, some companies have assumed the practice of providing a heavy derrick during the drilling period which is dismantled when the drill period is over. This heavy derrick is replaced by a lighter derrick which is sufficiently heavy for use during the pumping of the well.

It is an object of my invention to provide a derrick which is so constructed that it is sufficiently strong to withstand any strains which may be placed thereon during the drilling period, and is so constructed that portions thereof may be removed after the drilling of the well, greatly lightening the derrick and cutting down the investment therein. I accomplish this object of my invention by providing a structure which is substantially equivalent to the ordinary construction of light or pumping derrick. In addition to this, I provide reinforcing legs which are secured in place during the drilling of the well and which assist the main legs of the derrick in carrying great loads. When the drilling has been finished, these reinforcing legs may be removed from place, leaving the essential construction of the derrick to be used during the pumping operation of the well. These reinforcing legs may be used on various derricks, that is to

say, when the drilling has been completed on one derrick, they may be installed on another derrick which is being used during the drilling of a well. This provides a great saving in derricks, due to the fact that all derricks may be made only heavy enough to withstand the strains placed thereon during the pumping, the reinforcing legs being employed with these derricks when they are taking drilling duty.

It is another object of my invention to provide a means whereby the portion of the load taken by the main legs and the reinforcing legs may be adjusted. I accomplish this by providing inserts which are adapted to be inserted in such a manner as to increase the effective length of the reinforcing legs. When these reinforcing legs are installed in a derrick, they are adjusted in length so they may take any desired portion of the load. This insert arrangement also permits easy installation and removal of the reinforcing legs.

It is also an object of my invention to provide a reinforcing leg arrangement of this character which, when once installed, is permanent until steps are taken to remove it from place.

Further objects and advantages of my invention will be made evident hereinafter.

Referring to the drawing in which I illustrate a preferred form of my invention,

Fig. 1 is an elevational view through a corner of a derrick showing a reinforcing leg of my invention in place. The derrick in this view is shown very diagrammatically and is broken away so as to clearly show my invention.

Fig. 2 is a section taken on the line 2—2 of Fig. 1 showing the clamp members employed by my invention for holding the reinforcing legs in place.

Fig. 3 is an enlarged section of the lower end of a leg of the derrick.

Fig. 4 is a section taken on the line 4—4 of Fig. 3.

Fig. 5 is a section taken on the line 5—5 of Fig. 3.

Fig. 6 is a diagrammatic plan view on a much smaller scale showing the location of the main legs and the reinforcing legs of the derrick of my invention.

In the form of the invention illustrated in the drawings, I provide a derrick having four main legs in the form of angle-iron legs

11 which extend from foundations 12 to an upper structure 13. This upper structure 13 is composed of cross members 14 which form a construction on which the crown 5 block of the derrick rests. The legs 11 are connected together by suitable cross bracing which, for the purpose of simplicity, is not shown, this bracing however being of the general form of bracing used in oil well derricks. The angle-iron legs 11 are made amply strong to take care of any strains which may be placed thereon during the pumping period of the well, but they are not sufficiently strong to withstand the enormous 10 loads which are placed thereon during the drilling period of the well.

At the upper end of each of the angle-iron legs 11, as shown in Fig. 1, there is secured an upper thrust member 16 which may be 20 bolted to one of the legs 11 or to the lower cross member 14 of the top structure 13. Each of the upper thrust members 16 provides a socket 17 into which an upper end 18 of a reinforcing leg 19 extends, there being 25 a reinforcing leg 19 extending parallel with and adjacent to each of the main angle-iron legs 11. The reinforcing legs 19 are preferably made from a pipe, as shown. Near the lower end of each of the main legs 11 there is 30 secured a lower thrust member 22. This lower thrust member 22 has a tubular shaped body 23 which has a pair of plane faces 24 which are substantially at right angles to each other and which are adapted to engage 35 inner faces 24^a of the legs 25 of each of the main angle legs 11. Extending through heavy portions 26, adjacent to the faces 24, are bolts 27 which also extend through the legs 25 of each of the main legs 11 for the 40 purpose of securing each of the lower thrust members 22 in place. A lower face 28 of each of the reinforcing legs 19 engages an annular shoulder 29 of a head 30 of an abutment member 31. Each abutment member 45 31 has a stem 32 which extends downwardly from the head 30 through an opening 34 in a wall 35 of each of the lower thrust members 22.

Between a lower face 36 of each head 30 and an upper face 37 of the wall 35 of each lower thrust member 22, there is placed an insert means or insert member 39 which is composed of a number of shims 40. These shims 40, as shown in Fig. 4, are made in 50 two sections 41 for the purpose of facilitating their installation, as will be hereinafter described. A tubular shield or guard 43 is placed around the lower end of each of the reinforcing legs 19 and serves to enclose the 55 inserts 39. The shield 43 protects the inserts 39 and prevents their being accidentally removed from place. Clamp bolts 50, Fig. 2, are provided at various places along the legs 60 19 for securing them to the main legs 11.

65 The main angle legs 11, the foundations 12 and the top structure 13 are arranged to be used alone during the pumping of the well and are, therefore, permanently assembled together. The reinforcing legs 19 and their associated parts are used only during the pumping period of the well and are therefore made so as to be removable and to be auxiliary equipment. After the lighter derrick has been installed, the upper and lower thrust members 16 and 22 are secured in 70 place by suitable bolts. The reinforcing legs 19 are then installed in place along with the abutment member 31 and the guard 43. In order that the reinforcing legs 19 take part of the load of the derrick, it is necessary that they be placed under compression. To accomplish this, jacks are employed 75 which are adapted to engage the lower ends of the stems 32 of the abutment members 31. The jacks are operated so as to force the 80 abutment members 31 upwardly, thus forcing the reinforcing legs 19 upwardly therewith. When the reinforcing legs 19 are sufficiently under compression to take the desired portion of the load, shims 40 are placed 85 between the faces 36 and 37. The shims 40 are made in two semi-circular pieces 41 so that they may be placed around the upper end of the stem 32, as clearly shown in the drawings. After the shims 40 have been installed, the jacks are removed from place. More or less of the load of the derrick may be carried by the reinforcing legs 19 by installing a greater or less number of shims. During the placing of the shims 40, the 90 guards 43 are slipped upwardly on the reinforcing legs 19 to give access to the space between the heads of the lift members and the upper faces of the lower thrust members 22. After the installation of the shims, the 95 guards 43 are lowered into place, as clearly shown in Fig. 4, so that the shims will be protected against accidental removal from place.

From the foregoing description, it will be 100 seen that my invention is of great value from a standpoint of economy. It permits a fairly light construction of derrick to be installed which may be made sufficiently 105 strong to withstand strains during the drilling period of the well. After the drilling period is over, these reinforcing means which are in the form of legs 19 may be removed and used on other similar derrick constructions. The arrangement for elevating and 110 reinforcing legs 19 is very simple in construction and allows the legs to be adjusted to take any desired portion of the load of the derrick. When once the shims 40 are 115 installed, the effective length of each leg 19 is permanent and will not get out of adjustment. The device of the arrangement is of such design that it is cheap to produce and permits an easy installation and removal of 120 its various parts.

I claim as my invention:

1. In a steel derrick, the combination of: main legs; a top structure supported at and rigidly secured to the upper end of said main legs; an upper thrust member secured near the upper end of each of said main legs; a lower thrust member secured near the lower end of each of said legs; a reinforcing leg extending between each upper and lower thrust member, said reinforcing legs assisting said main legs in supporting said top structure; and insert means arranged to be placed between each of said reinforcing legs and one of said thrust members by virtue of which said reinforcing legs will carry a greater portion of the weight of said upper structure.

2. In a steel derrick, the combination of: main legs; a top structure supported at the upper end of said main legs; an upper thrust member secured near the upper end of each of said main legs; a lower thrust member secured near the lower end of each of said legs; a reinforcing leg extending between each upper and lower thrust member, said reinforcing legs assisting said main legs in supporting said top structure; insert means arranged to be placed between each of said legs and one of said thrust members by virtue of which said reinforcing legs will carry a greater portion of the weight of said upper structure; and abutment means for engaging each of said reinforcing legs to allow the latter to be moved so as to permit the placing of said insert means.

3. In a steel derrick, the combination of: main legs; a top structure supported at the upper end of said main legs; an upper thrust member secured near the upper end of each of said main legs; a lower thrust member secured near the lower end of each of said legs; a reinforcing leg extending between each upper and lower thrust member, said reinforcing legs assisting said main legs in supporting said top structure; insert means arranged to be placed between each of said legs and one of said thrust members by virtue of which said reinforcing legs will carry a greater portion of the weight of said upper structure; abutment means for engaging each of said reinforcing legs to allow the latter to be moved so as to permit the placing of said insert means; and means for enclosing said inserts.

4. In a steel derrick, the combination of: a top structure; a plurality of main legs for supporting said top structure; a plurality of upper thrust members, there being one of said upper thrust members secured at the upper end of each of said main legs; a plurality of lower thrust members, there being one of said lower thrust members secured at the lower end of each of said main legs; a plurality of reinforcing legs, one of said reinforcing legs being arranged adjacent to

each of said main legs and engaging one of said upper thrust members; a plurality of inserts, one of said inserts being arranged between one of said reinforcing legs and one of said lower thrust members; and a plurality of abutment members, one of said abutment members being arranged to engage one of said reinforcing legs to allow the latter to be moved so that one of said inserts may be installed.

5. In a steel derrick, the combination of: a top structure; a plurality of main legs for supporting said top structure; a plurality of upper thrust members, there being one of said upper thrust members secured at the upper end of each of said main legs; a plurality of lower thrust members, there being one of said lower thrust members secured at the lower end of each of said main legs; a plurality of reinforcing legs, one of said reinforcing legs being arranged adjacent to each of said main legs and engaging one of said upper thrust members; a plurality of inserts, one of said inserts being arranged between one of said reinforcing legs and one of said lower thrust members; a plurality of abutment members, one of said abutment members being arranged to engage one of said reinforcing legs to allow the latter to be moved so that one of said inserts may be installed; and a plurality of guards, one of said guards being placed so as to enclose one of said inserts.

6. In a steel derrick, the combination of: a top structure; a plurality of main legs for supporting said top structure; a plurality of upper thrust members, there being one of said upper thrust members secured at the upper end of each of said main legs; a plurality of lower thrust members, there being one of said lower thrust members secured at the lower end of each of said main legs; a plurality of reinforcing legs, one of said reinforcing legs being arranged adjacent to each of said main legs and engaging one of said upper thrust members; a plurality of inserts, each of said inserts comprising a number of shims, one of said inserts being arranged between one of said reinforcing legs and one of said lower thrust members; and a plurality of abutment members, one of said abutment members being arranged to engage one of said reinforcing legs to allow the latter to be moved so that one of said inserts may be installed.

7. In a steel derrick, the combination of: a top structure; a plurality of main legs for supporting said top structure; a plurality of upper thrust members, there being one of said upper thrust members secured at the upper end of each of said main legs; a plurality of lower thrust members, there being one of said lower thrust members secured at the lower end of each of said main legs; a plurality of reinforcing legs, one of said re-

inforcing legs being arranged adjacent to each of said main legs and engaging one of said upper thrust members; a plurality of inserts, each of said inserts comprising a number of shims, one of said inserts being arranged between one of said reinforcing legs and one of said lower thrust members; a plurality of abutment members, one of said abutment members being arranged to engage one of said reinforcing legs to allow the latter to be moved so that one of said inserts may be installed; and a plurality of guards, one of said guards being placed so as to enclose one of said inserts.

15 8. In a steel derrick, the combination of: a top structure; a plurality of main legs for supporting said top structure; a plurality of upper thrust members, there being one of said upper thrust members secured at the upper end of each of said main legs; a plurality of lower thrust members, there being one of said lower thrust members secured at the lower end of each of said main legs; a plurality of reinforcing legs, one of said reinforcing legs being arranged adjacent to each of said main legs and engaging one of said upper thrust members; a plurality of inserts, each of said inserts comprising a number of shims, which shims are composed of cooperating half-annular members, one of said inserts being arranged between one of said reinforcing legs and one of said lower thrust members; and a plurality of abutment members, one of said abutment members being arranged to engage one of said reinforcing legs to allow the latter to be moved so that one of said inserts may be installed.

9. In a steel derrick, the combination of: a top structure; a plurality of main legs for supporting said top structure; a plurality of upper thrust members, there being one of said upper thrust members secured at the upper end of each of said main legs; a plurality of lower thrust members, there being one of said lower thrust members secured at the lower end of each of said main legs; a plurality of reinforcing legs, one of said reinforcing legs being arranged adjacent to

each of said main legs and engaging one of said upper thrust members; a plurality of inserts, each of said inserts comprising a number of shims, which shims are composed of cooperating half-annular members, one of said inserts being arranged between one of said reinforcing legs and one of said lower thrust members; a plurality of abutment members, one of said abutment members being arranged to engage one of said reinforcing legs to allow the latter to be moved so that one of said inserts may be installed; and a plurality of guards, one of said guards being placed so as to enclose one of said inserts.

10. In a steel derrick, the combination of: main legs; a top structure rigidly secured to the upper ends of said main legs and being supported thereby; reinforcing legs, there being a reinforcing leg extending adjacent to one of said main legs; thrust members, one of same being placed adjacent to the lower ends of each of said reinforcing legs; and insert means, one of which being adapted to be placed between one of said reinforcing legs and one of said thrust members.

11. In a steel derrick, the combination of: main legs; a top structure rigidly secured to the upper ends of said main legs and being supported thereby; reinforcing legs, there being a reinforcing leg extending adjacent to one of said main legs; thrust members, one of same being placed adjacent to the lower ends of each of said reinforcing legs; abutment members, one of which being adapted to engage one of said reinforcing legs to allow the latter to be moved into supporting relationship with said top structure; and insert means, one of which being adapted to be placed between one of said reinforcing legs and one of said thrust members.

12. A combination as defined in claim 11 in which said lift members have stems, said stems being adapted to extend through openings in said thrust members.

In testimony whereof, I have hereunto set my hand at Los Angeles, California, this 6th day of May, 1925.

LESLIE A. RAWSON.
